CLAIM

The ornamental design for a range hood, as shown and described.

DESCRIPTION

FIG. 1 is a perspective view of a range hood showing our new design;

FIG. 2 is an alternative perspective view thereof;

FIG. 3 is a front elevation view thereof;

FIG. 4 is a rear elevation view thereof;

FIG. 5 is a side elevation view thereof;

FIG. 6 is an opposite side elevation view thereof;

FIG. 7 is a top plan view thereof; and,

FIG. 8 is a bottom plan view thereof.

The broken lines depict portions of the range hood that form no part of the claimed design.
